DESIGN.

O. ARNOLD.

PLAQUE.

No. 16,309.

Patented Oct. 6, 1885.

UNITED STATES PATENT OFFICE.

OTTO ARNOLD, OF BUCKAU, MAGDEBURG, PRUSSIA, GERMANY.

DESIGN FOR A PLAQUE.

SPECIFICATION forming part of Design No. 16,309, dated October 6, 1885.

Application filed August 13, 1885. Serial No. 174,351. Term of patent 7 years.

To all whom it may concern:

Be it known that I, OTTO ARNOLD, a citizen of the German Empire, residing at Buckau, Magdeburg, in the Kingdom of Prussia and 5 German Empire, have invented and produced a new and original Design for Plaques, of which the following is a specification.

The object of this design is to provide a novel and ornamental plaque; and it consists 10 in a plaque having a center bearing a bell, an eagle, and a shield, a plain ring around said center, a molding around the ring, and an annulus around the molding bearing olive leaves or foliage, and medallions separating the leaves 15 or foliage into sections, all as illustrated in the accompanying drawing, which is a face view of the plaque.

Referring to the drawing, the letter A indicates the center bearing an eagle with raised 20 wings, holding with the talons of one foot several arrows and with the talons of the other foot olive leaves or foliage. The eagle holds in its mouth a scroll, and on its breast is a shield displaying stars and stripes. Below 25 the eagle is a bell having a crack, F. Around the center A are moldings D, surrounded by a plain-faced ring, C. This ring is surrounded by moldings E, and around such moldings is the annulus B, bearing olive leaves or foliage 30 G, and medallions H, which separate the leaves or foliage into sections. The outer edge of the annulus B is bounded by a molding, I, surrounded by a row of radial bars, J, separated by spaces K, and around the radial bars 35 and spaces is a molding, L.

Having thus described my invention, what I claim is—

1. The design for a plaque, consisting of the center A, bearing an eagle, a shield, and a bell, the plain-faced ring C, and the annulus B, 40 bearing olive leaves or foliage G, and medallions H, substantially as shown.

2. The design for a plaque, consisting of the center A, bearing the eagle, the shield, and the bell, the moldings D, the plain-faced ring C, 45 the moldings E, and the annulus B, bearing the olive leaves or foliage G, and medallions H, substantially as shown.

3. The design for a plaque, consisting of the center A, the moldings D, the ring C, the moldings E, the annulus B, bearing olive leaves or foliage G, and medallions H, the molding I, the 50 surrounding radial bars J, spaces K, and an annular molding L, substantially as shown.

4. The design for a plaque, consisting of the center A, bearing the eagle, the shield, and the bell, the moldings D, the plain-faced ring C, the moldings E, the annulus B, bearing olive leaves or foliage G, and medallions H, the molding I, the radial bars J, the spaces K, and the molding L, 55 substantially as shown.

In testimony whereof I have hereunto set my hand and seal in the presence of two subscribing witnesses.

OTTO ARNOLD. [L. S.]

Witnesses:

WILLIAM C. FOX,
JOHN KRACKE.
